UNITED STATES PATENT OFFICE

106,118

DESIGN FOR A SWEATER ENSEMBLE

Sol Kurtz, New York, N. Y.

Application August 4, 1937, Serial No. 70,839

Term of patent 3½ years

To all whom it may concern:

Be it known that I, Sol Kurtz, a citizen of the United States of America, residing in the city of New York, county of New York, and State of New York, have invented a new, original, and ornamental Design for a Sweater Ensemble, of which the following is a specification, reference being had to the accompanying drawing, forming part thereof.

Fig. 1 is a front view of a sweater ensemble showing my new design.

Fig. 2 is a rear view thereof.

Fig. 3 is a front view of the sweater section of the ensemble.

The back of the sweater section is identical with the front.

I claim:

The ornamental design for a sweater ensemble substantially as shown and described.

SOL KURTZ.
